CLAIM

An ornamental design for an adapter for supporting an electronic device, as shown and described.

DESCRIPTION

FIG. 1 is a front, top, left perspective view of an adapter for supporting an electronic device;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in FIGS. 1-7 illustrate portions of the adapter for supporting an electronic device that form no part of the claimed design.

1 Claim, 4 Drawing Sheets
